UNITED STATES PATENT OFFICE.

MALCOLM STEAURT McQUARRIE, OF PASO ROBLES, CALIFORNIA.

DESIGN FOR A CHAIR-BRACE.

SPECIFICATION forming part of Design No. 18,607, dated September 11, 1888.

Application filed June 9, 1888. Serial No. 276,655. Term of patent 14 years.

To all whom it may concern:

Be it known that I, MALCOLM STEAURT McQUARRIE, a citizen of the United States, residing at Paso Robles, in the county of San Luis Obispo and State of California, have invented a new and useful Design for Chair-Brace, of which the following is a specification.

My invention relates to a design for chair-brace, which is fully described hereinafter in connection with the accompanying drawings, wherein—

Figure 1 is a perspective view of the chair-brace made in accordance with my design. Fig. 2 is a central vertical sectional view of the same.

Referring to the drawings, the leading feature of my design consists in a yoke having the diverging arms A A and the curved and flattened portion B, connecting the adjacent ends of the said arms. The diverging arms are arranged in the same plane, and are inclined to the inner face of the said curved and

flattened portion B. An aperture, C, is formed in the curved and flattened portion at its center, and the upper ends of the divergent arms are provided with ears D D, the upper faces of which are perpendicular to the inner face of the curved portion B. The ears are provided with apertures E E.

Having thus described the invention, I claim—

The design for a chair-brace herein shown and described, consisting of a yoke having divergent arms A A, provided with apertured ears, and connected by a curved and flattened portion, B, provided with an aperture, substantially as specified.

In testimony that I claim the foregoing as my own I have hereto affixed my signature in presence of two witnesses.

MALCOLM STEAURT McQUARRIE.
